UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT FOR FURNITURE.

SPECIFICATION forming part of Design No. 26,901, dated April 13, 1897.

Application filed December 26, 1896. Serial No. 617,110. Term of patent 7 years.

To all whom it may concern:

Be it known that I, FREDERICK W. CHESSON, a citizen of the United States, residing at Waterbury, in the county of New Haven and State of Connecticut, have invented and produced a new and original Design for Metal Mounts for Furniture, &c., of which the following is a specification, reference being had to the accompanying drawings, in which—

Figure 1 is an elevation, Fig. 2 a vertical section, and Fig. 3 a plan, which fully illustrate my design.

The leading features of my design consist in the central convex portion of the body, the annular beads at each side thereof, and adjacent contracted portions.

The central convex portion of the body is represented at *a*, and *b* *b'* are the annular beads at each side of said central convex

portion. Above the bead *b* the body portion *c* is contracted and coved at *c'*, and extending upward from said cove *c'* the body portion comprises the bead *d*, the ring portions *e*, *e'*, and *e''*, the coves *f* and *f'*, and the globular head *g*. Below the annular bead *b'* the contracted body comprises the curved portion *h*, the ring portions *i* *i'*, and the coved portion *k*.

What I claim is—

The design for a metal mount for furniture, &c., substantially as herein shown and described.

Signed by me this 17th day of December, A. D. 1896.

F. W. CHESSON.
